UNITED STATES PATENT OFFICE.

FREDERIC W. PARKHILL, OF ARKANSAS CITY, KANSAS, ASSIGNOR OF ONE-HALF TO
LEONARD V. COWAN, OF ARKANSAS CITY, KANSAS.

GOLF TEE.

Application filed April 17, 1924. Serial No. 707,117.

My invention relates to golf tees and has for its object to provide a portable tee for supporting the golf ball in an elevated position from the ground, preparatory to being driven.

A further object of the invention is to provide a tee having means for limiting its insertion in the ground, so the ball will be elevated the proper distance from the ground, 10 and means whereby it may be readily and easily extracted from the ground after serving its purpose.

Another object of the invention is to provide a device of this character which is 15 simple and durable in construction, efficient and convenient in use and inexpensive to manufacture.

Other objects and advantages of the invention will be apparent during the course 20 of the following description.

In the accompanying drawing, forming a part of this specification and in which like numerals are employed to designate like parts throughout the same,

25 Figure 1, is a perspective view of the tee in use,

Figure 2, is a side elevation of the tee, and,

20 Figure 3, is a vertical sectional view of the same.

Referring to the drawing, wherein for the purpose of illustration I have shown a preferred embodiment of my invention the numeral 5 denotes generally the improved tee 35 which consists of a head 6 having a reduced shank 7, constructed of wood or other suitable material. The head 6 is substantially flat and preferably of circular configuration. The shank 7 extends axially from the 40 head, and is tapered so it may be easily driven into the ground to anchor the tee in position. The horizontal annular shoulder 8, on the underside of the head, at the jointure of the shank 7 with the 45 head, limits the insertion of the shank upon contact with the ground and also serves to support the tee in a firm upright position. The peripheral edge of the shoulder is

chamfered, as at 9, so the head may be easily gripped to remove the tee from the 50 ground. The top 10 of the head is concaved to provide a seat or recess to receive the golf ball 11.

In use, it will be seen the shank may be easily driven into the ground by pressing 55 with the finger on the top of the head. Insertion of the shank is limited by the shoulder on the underside of the head which will contact with the ground and prevent the tee from being driven into the 60 ground too far. The removal of the tee is facilitated by the chamfered edge of the shoulder which leaves a recess between the ground and the head after the tee is driven in the ground, which permits the head to 65 be readily grasped by the fingers. Thus, it is seen the device provides a portable tee which is efficient in use and may be conveniently carried by the player.

It is to be understood that the form of my 70 invention herewith shown and described is to be taken as a preferred example of the same and that certain changes in the shape, size and arrangement of parts may be resorted to without departing from the spirit 75 of the invention or the scope of the subjoined claims.

Having thus described my invention, I claim:

A golf tee formed from a single piece of 80 material, comprising a tapered shank and an enlarged flat head connected with and carried by the upper end of said shank, said head having its upper surface concaved to form a seat for supporting the ball, said 85 shank being disposed axially with relation to said head, the underside of said head surrounding said shank being on a horizontal plane at right angles to the longitudinal axis of said shank, with its peripheral edge beveled inwardly for the insertion 90 of means to extract the tee from the ground.

In testimony whereof I affix my signature.

FREDERIC W. PARKHILL.
